PORTABLE DEVICE FOR PROCESSING FUR
OR THE LIKE

Max Koch, New York, N. Y., assignor of fifty per cent to Florence K. Edelstein and fifty per cent to Melvin J. Koch, both of New York, N. Y.

Application January 14, 1947, Serial No. 721,985

19 Claims. (Cl. 69—20)

1

This invention relates to portable devices for processing fur or fur garments or piled sheets.

An object of this invention is to provide a highly improved machine of the character described having means for combining brushing, ironing, and cleaning fur or like material having a pile or hair, and for producing a sheen and generally improving the appearance of fur or fur garments.

Another object of this invention is to provide a device or machine of the character described which shall have the following features or parts:

1. A nose which carries roller and heating unit, is removable in order to facilitate change of roller, change of heating unit, and making adjustment or change in gears which drive the roller.

2. Fire walls: One between a motor chamber and a pulley compartment and one between the pulley compartment and the blower housing (air rotor housing). The fire walls keep heat of roller (400° F.) out of pulley housing and away from motor.

3. The air rotor housing is placed and designed so as to suck and control the air from the bottom opening of the machine, and yet not cause any air turbulence which would produce back pressure. Air rotor housing is mounted on the forward fire wall.

4. A base removable for accessibility and repair of workable parts of machine.

5. A handle arranged so as to be forward of center of gravity in order to balance the motor which is at the back of the machine and is heavier than the nose of the machine, so that as the machine is used, the tendency is to push the nose forward and down and so keep the base in a horizontal plane. When at rest the machine tilts back so as to keep the hot roller off the table or work.

6. The wires through the handle. The handle is so designed (split hollow handle) as to receive wires without exposing same to heat. The handle is insulated so as not to heat up. Location of switch makes it readily accessible to fingers of operator when using machine.

7. The thermostat controls the heat unit in roller through range of 90° F. to 400° F. Knob for thermostat is located in accessible place. Thermostat is in housing to one side where there is room for it.

8. Gearing: No belt for roller, that is between air rotor and roller. Right angle drive is made operative through a worm gear arrangement through longitudinal center line of machine. A counter shaft is supported off left hand wall of casing to which is connected a reduction gear which drives the roller.

2

9. Eye bolts for a counter balance (three eye-bolts).

10. The bolts to bolt the handle to the casing. If wiring goes wrong, it is only necessary to take out two bolts which bind handle to housing studs and to pull the handle up for wiring adjustment or repairs. If further wiring repair to handle is necessary removal of the upper two screws which hold both halves of handle together will expose all wiring for necessary adjustment.

15. Yet another object of this invention is to provide a strong, compact and light machine of the character described which shall be relatively inexpensive to manufacture, easy to handle, and yet practical and efficient to a high degree in use.

Other objects of this invention will in part be obvious, and in part hereinafter pointed out.

The invention accordingly consists in the features of construction, combinations of elements, and arrangement of parts which will be exemplified in the construction hereinafter described, and of which the scope of application will be indicated in the following claims.

25. In the accompanying drawing, in which is shown various possible illustrative embodiments of this invention.

Fig. 1 is a top plan view of a machine embodying the invention;

30. Fig. 2 is a cross-sectional view taken on line 2—2 of Fig. 1;

Fig. 3 is a cross-sectional view taken on line 3—3 of Fig. 2;

Fig. 4 is a cross-sectional view taken on line 4—4 of Fig. 2;

35. Fig. 5 is a front end view of the improved machine;

Fig. 6 is a partial side elevational view of the machine;

Fig. 7 is a cross-sectional view taken on line 7—7 of Fig. 3;

Fig. 8 is a cross-sectional view taken on line 8—8 of Fig. 3;

Fig. 9 is a wiring diagram of the electrical circuit for the device embodying the invention;

Fig. 10 is a transverse cross-section of the roller;

Fig. 11 is a cross-sectional view taken on line 11—11 of Fig. 3;

Fig. 12 is a cross-sectional view taken on line 12—12 of Fig. 3; and

Fig. 13 is a partial cross-sectional view of the roller and heater assembly.

Referring now in detail to the drawing, 10 designates a portable device for processing fur, embodying the invention. The device 10, as will

appear hereinafter, may be manually moved over a piece of fur or garment or other material provided with a pile, for ironing, combing and brushing the fabrics or hairs and for applying a sheen or luster to the fabrics, and also for cleaning said garment or fur or fabric of dust.

The device 10 comprises a motor casing 11, having a cylindrical wall 12 formed with an integral hemispherical wall 13 at one end. At the open end of casing 11 is an outwardly extending angular flange 14. Wall portion 13 is formed with a plurality of ventilating openings 15. Said housing is furthermore formed on the inside thereof with a pair of spaced longitudinally extending ledges 16. The ledges 16 are spaced from one another and each is formed with a horizontal upper surface 17. Each ledge is furthermore formed with a smooth depressed surface 18. Mounted within the casing 11 is an electric motor 20. The base of the motor rests on surfaces 18 of ledges 16. Each of the ledges is formed with a pair of vertical through openings 21 countersunk at the lower end to receive screws secured into the base for attaching the motor to the housing.

Housing 11 is formed with an upwardly extending stud 23, for the purpose hereinafter appearing. It is also formed adjacent said stud with a through opening 24. The stud 23 and opening 24 are in a vertical plane passing through the axis of the housing. Stud 23 is formed with a horizontal transverse through opening 25 for the purpose hereinafter appearing. Attached to the casing 11 are a pair of spaced eyelets 26 located in the same vertical plane perpendicular to the axis of the housing. The purpose of the eyelets 26 will appear hereinafter.

Attached to the front open end of the housing 11 is a motor housing plate 30. Said plate 30 is attached to flange 14 by screws 31 and 32, passing through suitable openings in said flange and plate. Said plate 30 has a straight thickened forwardly extending flange 33 at its lower end disposed below the motor housing. Said plate 30 has a semi-circular top edge 34 and straight side edges 35 being of inverted U-outline. It is formed with a straight opening 36 through which the hub 37 of the motor passes. Extending from the hub of the motor is an armature stud shaft 38 for the purpose hereinafter appearing.

Attached to the front of plate 30 is a pulley housing or fire wall 40. Said housing 40 is formed with a semi-circular top wall 41 from which there extends downwardly parallel side walls 42. At the rear of walls 41 and 42 is an outwardly extending flange 43 contacting the front surface of plate 30. Flange 43 is formed with countersunk openings 43a registering with screw threaded openings 44 in plate 30 to receive attaching studs 45 which serve to attach housing 40 to plate 30. At the front of walls 40, 41 is a wall 46 parallel to plate 30 and extending downwardly below the lower ends of side walls 42. Wall 46 has a horizontal lower edge 47. Said wall 46 is formed below the radial center of curved wall 41 with a through opening 48 in which is mounted a ball bearing 49.

Attached to the front face of wall 46 is an air rotor housing 51. Said air rotor housing is formed with a cylindrical wall 52 from which there extends outwardly an angular flange 53 contacting the front surface of wall 46. Flange 53 may be cut away at its lower end. It is formed with screw threaded openings to receive screws 54 passing

through suitable openings in plate 45 for attaching housing 51 to housing 40. Opening 48 is axially disposed relative to housing 51. Housing 51 is furthermore formed with the front inwardly extending angular flange 55.

Attached to the front of wall 46 of member 40 is a cover member 60. Said cover 60 comprises parallel vertical side walls 61 from which extends upwardly and inwardly, inclined walls 62 joined by a top curved wall 63. Extending upwardly from the top wall 63 is an integral vertical stud 64, similar to stud 23 and formed with a transverse through opening 65. The side wall 61 has aligned lower edges 66. Said cover 15 is furthermore formed with a thickened front wall 67, interconnecting the front ends of the side walls 61. Between the front wall 61 and walls 62, 63 is a curved wall 68. The front of the lower edge of the front wall 67 is cut away from a horizontal undersurface 69 extending to a front vertical shoulder 70.

Extending upwardly from one of the inclined walls 62 is a flanged opening or sleeve 73, see Fig. 4 for the purpose hereinafter appearing. Wall 67 is formed with an internal vertical surface 74. Said surface 74 is formed with a curved notch 75, see Fig. 8 at one end thereof for the purpose hereinafter appearing. Wall 67 is formed with a horizontal longitudinal through opening 77 coaxial with opening 48 in the front wall of the pulley housing 40. The outer end of opening 77 is screw-threaded and screwed therein is a set screw 78. Within said opening and contacting the set screw is a thrust ball bearing 79. At the inner surface of wall 74 is a recess 80 co-axial with opening 77 and receiving a ball bearing 81. Extending through the ball bearings 81 and 49 is a horizontal longitudinal shaft 82, and secured thereto, a worm 83. It is to be noted that the thrust ball 79 is interposed between the set screw 78 and the adjacent end of shaft 82.

Shaft 82 projects into the pulley chamber 84 formed by the pulley housing or fire wall 40. On shaft 38 is a pulley 85, interposed within the pulley chamber. On shaft 82 is a pulley 86 disposed within the pulley chamber. Interconnecting said pulleys 85 and 86 is a belt 88. On shaft 82 and interposed within the air rotor housing 51 is an air rotor or fan 90.

Attached to the bottom of the cover and closing the bottom of the pulley chamber 84 is a base plate 92. Said base plate 92 comprises a bottom wall 93 from which there extends upwardly side walls 94. The upper edges of walls 94 contact the lower edges 66 of the cover walls 61. Said bottom wall 93 terminates short of the front edges of side walls 94. Said side walls 94 have front ends 95 which are in alignment with edges 70 of the cover. Extending upwardly from wall 93 is a partition wall 96 having a curved upper edge 97 disposed below the rotor housing wall 52. At the rear of the base plate 92 is an upwardly extending thickened wall 98 having a front surface 99 contacted by plate 46. Screws 100 passing through the lower corner portions of the plate 46 serve to attach plate 46 to surface 99. Said portion 99 furthermore has a rear surface 101 contacting flange 33. Screws 102 serve to attach said flange 33 to the thickened portion 98 of the base plate. The front edges 95 of side walls 94 are formed with semi-circular recesses 104 at their inner surfaces. The recesses 104 have countersunk semi-circular enlarged portions 105, as shown in Fig. 7.

Fitted at the front of the base plate and at the

lower end of front wall 67 of the cover is a nose member or roller support 110. Said roller support has a top straight arm 111 provided with surfaces contacting surfaces 69 and shoulder 70 of the cover. Inclined downwardly and forwardly from wall 111 is a wall 112 from which there extends a downwardly and inwardly curved arm 113. The rear edge 113a of arm 113 is parallel to and spaced from the forward edge 114 of the bottom wall 93 of the base plate, thereby forming an opening 115 in the bottom of the machine. At the ends of member 110 are end walls 116 having back edges 117 contacting surfaces 70 and 95 of the cover 60, and base plate 92, respectively. Said side walls 116 are formed adjacent the rear edges with semi-circular recesses 118 complementary to the recesses 104 and forming therewith circular openings. At the inner sides of the walls 116 and 94 are formed annular recesses 119 to receive ball bearing races 120. The nose member or roller housing 110 is attached to wall 67 by means of screws 121 passing through walls 111 and 67 and to front edges 95 of side walls 94 by screws 123.

On the curved wall 68 of the cover 60 is an eyelet 125 similar to the eyelets 26. It will now be observed that the machine can be hung on a counterbalance by engaging the eyelets 26 and 125.

The wall 61 adjacent the notch 75 is formed with a horizontal through opening 130. The outer end of the opening is screw threaded to receive a set screw 131. Within said opening is a ball bearing 132. Attached to the inner surface 74 of front wall 67 is an angular bearing bracket 133 having an arm 134 contacting said inner surface and an arm 135 extending at right angles thereto and parallel to the wall 61, which has the opening 130. It will be noted that the shaft 82 is located between arm 135 and the last mentioned wall 61. Arm 135 carries a bearing 136 aligned with the bearing 132. Rotatably mounted on said bearings is a horizontal transverse shaft 137 disposed below shaft 82. On shafts 137 is a worm wheel 138 meshing with the worm 83. Fixed to said shaft 137 and adjacent the inner surface of the wall 61 which has the opening 130 is a pinion 140.

Rotated on the ball bearings 119 is a roller 141. Mounted on one end of the roller is a pinion 142 meshing with the gear of pinion 140. Said roller is formed with an axial through opening 144 through which there passes a heating unit 145 received within the bearings 119. Said roller 141 is located between the side walls 94 of the base plate and between the side walls 116 of the roller support. Said roller 141 is formed with a pair of opposite flat surfaces 147. Extending from said flat surfaces 147 are part cylindrical surfaces 148. Said part cylindrical surfaces 148 terminate in helical edges 149. Extending from the edges 149 are undercuts 150, also extending helically. Extending from the bottom of the undercut surface 150 to the flat surfaces 147 are part cylindrical surfaces 151. Attached to the roller on each of the flat surfaces 147 is a helical row of combing pins 152. The roller may be formed with drilled openings extending to the axial opening 144 thereof, and the pins 152 are force fitted into said openings and extend therefrom.

The heater 145 extends through the axial opening 144 and heats the roller. It will now be understood that when the motor is operating, the rotor fan will rotate through belt 88 and shaft

82 and the roller will rotate through pinions 142 and 140, shaft 137, worm wheel 138, worm 83 and shaft 82. The motor thus serves to rotate the roller and at the same time rotates the fan 90. The fan is so arranged as to provide a suction through the opening 115, thereby causing air to blow upwardly through sleeve 73. The fur or other material over which the machine is moved will be combed by the teeth 152, will be ironed by the surfaces 148, will be brushed by the edges 149 and will be heated by the heated roller.

Mounted on sleeve 73 is an outlet member or can 150a. Said outlet can 150a comprises a vertical tube 151a fitted within sleeve 73. The lower end of tube 151a communicates with the interior of the air rotor housing 51 through wall 52. Attached to the upper end of tube 151a is a horizontal outwardly extending tube 152a. Extending from the upper end of sleeve 151a is an upwardly inclined baffle plate 153. At the outer end of tube 152a is an adapter 154 carrying a screen 155. The air passing outwardly through tube 152a is thus screened by the screen 155.

Dust collected within the can or outlet tube 25 may be removed and cleaned, if desired. The adapter 154 is preferably mounted on tube 152 by means of bayonet pins 156, which pass through appropriate bayonet slots in said tube. Interconnecting the studs 23 and 64 is a handle 160. The handle may be made of Bakelite or other heat 30 and electrically insulating material. It is split longitudinally and is hence formed of two parts 161 and 162. The parts 161, 162 have meeting surfaces 163. Said handle parts each have a straight portion 165 and downwardly and outwardly inclined portions 166 and 167. The part 35 162 is formed with a slot or groove 168 extending from one end to the opposite end thereof. The slot 168 is, of course, covered by handle part 161.

40 Wall 68 of the cover 60 is formed with an opening 170 adjacent the stud 64. Opening 24 communicates with one end of groove 168, whereas opening 170 communicates with the other end of the groove 168. A conduit is thus formed 45 interconnecting the motor housing 11 with the front housing or cover 68. Suitable wiring for the motor passes through the groove 168. The handle parts 161, 162 are formed with complementary grooves 172 at their meeting faces, to 50 form a socket to receive the stud 23. Said handle parts are also formed with complementary recesses 172 at their meeting faces to receive stud 64. Between the studs 23, 64 and the handle parts are insulating spacers or sleeves 176. Between the rear end of the handle and the motor 55 housing is a heat insulating spacer plate 180. Between the front end of the handle and the housing 60 is a similar spacing plate 182. Within the openings 25 and 65 of the studs 23 and 64, 60 respectively, are bushings or sleeves through which extend bolts 184 for fixing the handle to said studs. The handle parts are furthermore interconnected by transverse bolts 185. Within the handle formed by the cover 68 and attached 65 to the inner surface of one of the inclined walls 62 and adjacent the end of the chamber where the pinion or gear 140 is located, is a thermostat 190 controlled by a knob 191, disposed at the outside of the cover. The knob is provided with 70 a shaft 192 passing through a suitable opening in the cover for operating the thermostat. Such thermostat may be of well known construction, such as Model A-100 manufactured by General Thermostat Company of New York.

75 On the handle part 162 is a toggle switch 195

provided with a toggle lever 197 which projects inwardly with the handle. The switch is preferably located at the forwardly and downwardly inclined portion 167 of the handle, so that the person holding the handle may easily operate the switch with one of the fingers holding the handle.

In Fig. 9 there is shown a wiring diagram for the machine, embodying the invention. In the drawing, the motor 20 and a switch 195 are connected in a series circuit by wire 196 to a plug 197, which may be inserted in any suitable outlet. The thermostat 190 is connected in series circuit with the heating unit 145 by wire 198. The thermostat and heating unit are connected in series circuit to the plug 197 and are parallel to switch 195 and motor 20. Thus, the motor can be turned on while the thermostat is set to zero. Preferably the thermostat may be adjusted from zero to 400° F., although any suitable adjustment may be provided for. Furthermore, the heating unit may be turned on independently of operating the motor.

The wiring is not shown on the machine but is suitably connected to the motor terminals and switch 195 and thermostat 190, and is also attached to the heating unit 145, preferably at a point between the pinion 142 and the adjacent side wall 94 of the base plate. The wiring terminals to the heating unit are brought in through a groove 199 formed in the side wall 94 of the base plate as shown in Fig. 13.

It will now be understood that the nose or roller support which carries the roller and the heating unit is removable in order to facilitate change of rollers or change of heating unit, or for making adjustment or change in the gears which drive the roller.

Furthermore, it will be noted that there are two fire walls, one between the motor change and the pulley compartment, and one between the pulley compartment and the blower housing or air rotor housing. The fire walls keep heat of the roller out of the pulley housing and away from the motor.

The air rotor housing is placed and designed so as to suck and control the air from the bottom opening of the machine, and yet not cause any turbulence which would produce back pressure.

It will be further observed that the base plate is removable for accessibility and repair of the workable parts of the machine. This is accomplished by first unscrewing cover 60 from pulley housing 40. The screws 100 then become exposed for removal. The base plate 92 is finally removed by unscrewing screws 102.

The handle is arranged so as to be forward of the center of gravity of the machine in order to balance the motor, which is at the back of the machine, and is heavier than the nose. As the machine is used, the tendency of the operator is to push the nose forwardly and downwardly, and so keep the base in a horizontal plane. When the machine is at rest, however, it tilts back so as to keep the hot roller off the table or work.

The wires passing through the handle are thereby hidden and not exposed, and are insulated. The switch to control the motor is so located as to be accessible to the fingers of the operator when using the machine.

The thermostat controls the heat unit in the roller. The knob for the thermostat is located in an accessible place. The thermostat is in the housing and to one side where there is ample room for it.

The roller is connected to the air rotor by gearing and without any belts.

The handle is connected to the casing by means of bolts passing through studs on the casing. If the wiring goes wrong, the handle may be lifted as a whole away from the housing by removing a pair of bolts which pass through the studs. If further wiring repair in the handle is necessary, the two handle parts may be separated by removing two screws which hold both halves of the handle together, thereby exposing all the wiring for necessary adjustment. The machine is easy to use and may be hung on a counterbalance to facilitate movement thereof.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. A device of the character described comprising a motor casing, a pulley casing attached to the motor casing, a cover attached to the pulley casing, a base plate at the lower ends of the pulley casing and cover, an air rotor casing attached to the pulley casing and disposed within said cover, an electric motor within the motor casing and provided with an armature shaft projected into the pulley casing, an air rotor shaft parallel to the armature shaft and mounted for rotation on the pulley casing and cover, an air rotor within the air rotor housing and mounted on said air rotor shaft, said air rotor shaft passing through the rotor housing, pulleys on said armature shaft and air rotor shaft and disposed within said pulley casing, a belt interconnecting said pulleys, a transverse shaft mounted for rotation within said cover, worm and worm wheel means interconnecting the air rotor shaft with the transverse shaft, a nose member attached to the cover and forming an opening with the base plate at the bottom of said device, a roller mounted for rotation above said opening, and gear means interconnecting the transverse shaft and roller.

2. A device of the character described comprising a motor casing, a pulley casing attached to the motor casing, a cover attached to the pulley casing, a base plate at the lower ends of the pulley casing and cover, an air rotor casing attached to the pulley casing and disposed within said cover, an electric motor within the motor casing and provided with an armature shaft projected into the pulley casing, an air rotor shaft parallel to the armature shaft and mounted for rotation on the pulley casing and cover, an air rotor within the air rotor housing and mounted on said air rotor shaft, said air rotor shaft passing through the rotor housing, pulleys on said armature shaft and air rotor shaft and disposed within said pulley casing, a belt interconnecting said pulleys, a transverse shaft mounted for rotation within said cover, worm and worm wheel means interconnecting the air rotor shaft with the transverse shaft, a nose member attached to the cover and forming an opening with the base plate at the bottom of said device, a roller mounted for rotation above said opening, gear means interconnecting the transverse shaft and roller, said roller having an axial through opening, and a heating unit passing through said

opening and supported on and between said cover and nose member.

3. A device of the character described comprising a motor casing, a pulley casing attached to the motor casing, a cover attached to the pulley casing, a base plate at the lower ends of the pulley casing and cover, an air rotor casing attached to the pulley casing and disposed within said cover, an electric motor within the motor casing and provided with an armature shaft projected into the pulley casing, an air rotor shaft parallel to the armature shaft and mounted for rotation on the pulley casing and cover, an air rotor within the air rotor housing and mounted on said air rotor shaft, said air rotor shaft passing through the rotor housing, pulleys on said armature shaft and air rotor shaft and disposed within said pulley casing, a belt interconnecting said pulleys, a transverse shaft mounted for rotation within said cover, worm and worm wheel means interconnecting the air rotor shaft with the transverse shaft, a nose member attached to the cover and forming an opening with the base plate at the bottom of said device, a roller mounted for rotation above said opening, gear means interconnecting the transverse shaft and roller, and an insulating handle interconnecting the motor casing with the cover.

4. A device of the character described comprising a motor casing, a pulley casing attached to the motor casing, a cover attached to the pulley casing, a base plate at the lower ends of the pulley casing and cover, an air rotor casing attached to the pulley casing and disposed within said cover, an electric motor within the motor casing and provided with an armature shaft projected into the pulley casing, an air rotor shaft parallel to the armature shaft and mounted for rotation on the pulley casing and cover, an air rotor within the air rotor housing and mounted on said air rotor shaft, said air rotor shaft passing through the rotor housing, pulleys on said armature shaft and air rotor shaft and disposed within said pulley casing, a belt interconnecting said pulleys, a transverse shaft mounted for rotation within said cover, worm and worm wheel means interconnecting the air rotor shaft with the transverse shaft, a nose member attached to the cover and forming an opening with the base plate at the bottom of said device, a roller mounted for rotation above said opening, gear means interconnecting the transverse shaft and roller, an insulating handle interconnecting the motor casing with the cover, a switch on said handle, and wiring interconnecting a motor with the switch and passing through said handle.

5. A device of the character described comprising a casing having a base plate, said base plate being formed with a pair of semi-circular notches, a nose piece attached to the base plate and being formed with semi-circular notches complementary to the first-mentioned semi-circular notches and forming bearing openings therewith, a roller mounted on and between said bearing openings, said casing being formed with a longitudinal opening between the base plate and nose piece and below said roller, and means in said casing to rotate said roller.

6. A device of the character described comprising a casing having a base plate, said base plate being formed with a pair of semi-circular notches, a nose piece attached to the base plate and being formed with semi-circular notches complementary to the first-mentioned semi-circular notches, and forming bearing openings therewith, a roller

mounted on and between said bearing openings, said casing being formed with a longitudinal opening between the base plate and nose piece and below said roller, means in said casing to rotate said roller, and a heating unit passing through said roller and supported on and between said base plate and roller.

7. A device of the character described, comprising a casing, a nose piece attached to the casing, said casing being formed with a longitudinal opening at its underside adjacent said nose piece, said casing and nose piece being formed with complementary notches forming bearing openings, a roller mounted for rotation on and between said bearing openings, an electric motor within the casing, and means interconnecting the motor with the roller for rotating the latter.

8. A device of the character described, comprising a casing, a nose piece attached to the casing, said casing being formed with a longitudinal opening at its underside adjacent said nose piece, said casing and nose piece being formed with complementary notches forming bearing openings, a roller mounted for rotation on and between said bearing openings, an electric motor within the casing, means interconnecting the motor with the roller for rotating the latter, said casing being formed with a pair of upwardly extending studs, and an insulating handle having portions thereof attached to said studs.

9. A device of the character described, comprising a casing, a nose piece attached to the casing, said casing being formed with a longitudinal opening at its underside adjacent said nose piece, said casing and nose piece being formed with complementary notches forming bearing openings, a roller mounted for rotation on and between said bearing openings, an electric motor within the casing, means interconnecting the motor with the roller for rotating the latter, said casing being formed with a pair of upwardly extending studs, and an insulating handle having portions thereof attached to said studs, and said handle comprising a pair of substantially similar symmetrically disposed parts, having mutually contacting meeting surfaces, and means for attaching said handle parts together.

10. A device of the character described, comprising a casing, a nose piece attached to the casing, said casing being formed with a longitudinal opening at its underside adjacent said nose piece, said casing and nose piece being formed with complementary notches forming bearing openings, a roller mounted for rotation on and between said bearing openings, an electric motor within the casing, means interconnecting the motor with the roller for rotating the latter, said casing being formed with a pair of upwardly extending studs, and an insulating handle having portions thereof attached to said studs, and said handle comprising a pair of substantially similar symmetrically disposed parts, having mutually contacting meeting surfaces, and means for attaching said handle parts together, one of said handle parts being formed at its meeting surface with a conduit for wiring for the motor.

11. A device of the character described, comprising a casing, a nose piece attached to the casing, said casing being formed with a longitudinal opening at its underside adjacent said nose piece, said casing and nose piece being formed with complementary notches forming

bearing openings, a roller mounted for rotation on and between said bearing openings, an electric motor within the casing, means interconnecting the motor with the roller for rotating the latter, said casing being formed with a pair of upwardly extending studs, an insulating handle having portions thereof attached to said studs, and said handle comprising a pair of substantially similar symmetrically disposed parts, having mutually contacting meeting surfaces, means for attaching said handle parts together, one of said handle parts being formed at its meeting surface with a conduit for wiring for the motor, and a switch on said handle.

12. A portable fur processing device, comprising a casing including an undersurface having a front part extending below a rear part thereof, an insulating strap handle having the ends thereof attached to the casing and projecting above said casing, a motor in said rear part of the casing, a roller in the forward end of the said front part of the casing, means interconnecting the motor with the roller for rotating the latter when the former is energized, the middle of the handle being located forwardly of the center of gravity of said device, said device being adapted to be placed on a horizontal surface in tilted relation thereto with said rear part of the casing and the rear end of the front part of the casing in contact with said surface and the roller raised from said surface.

13. A portable fur processing device, comprising a casing, an insulating strap handle having the ends thereof attached to the casing and projecting above said casing, a motor in the rear part of the casing, a roller in the front part of the casing, means interconnecting the motor with the roller for rotating the latter when the former is energized, the middle of the handle being located forwardly of the center of gravity of said device, the front part of the casing extending below the rear part of the casing, so that when the device is in use, the rear part of the casing must be lifted, and when the device is not in use, the rear part of the casing will tilt downwardly to raise the roller above the surface on which the machine rests.

14. A portable fur processing device comprising a casing, a transverse fire wall within said casing, dividing the rear part of the casing from the front part of the casing, a motor in the rear part of the casing, a shaft passing through said transverse wall, a pulley interconnecting the motor with said shaft, an air rotor on said shaft and disposed within the front part of the casing, said casing being formed at its underside and adjacent its forward end with a transverse opening, a roller rotatably mounted within the front part of the casing and above said transverse opening, means interconnecting said shaft with the roller for rotation, and a heating unit within said roller.

15. A device of the character described, comprising a motor casing open at its front end, a plate attached to the front end of the casing and extending below said casing, a pulley housing attached to said plate and extending below said plate, a base plate attached to the pulley housing and plate, the undersurface of the base plate being disposed below said motor casing, a cover member attached to the pulley housing and base plate, and forming a chamber therewith, a nose member attached to said cover member and base plate, a transverse opening being formed between the base plate and the nose member at the under-

side of said device, a roller rotatably mounted between said nose member and base plate, and being removable upon removing said nose member, a motor in said motor casing, and means interconnecting said motor and roller for rotation.

16. A device of the character described, comprising a motor casing open at its front end, a plate attached to the front end of the casing and extending below said casing, a pulley housing attached to said plate and extending below said plate, a base plate attached to the pulley housing and plate, the undersurface of the base plate being disposed below said motor casing, a cover member attached to the pulley housing and base plate, and forming a chamber therewith, a nose member attached to said cover member and base plate, a transverse opening being formed between the base plate and the nose member at the underside of said device, a roller rotatably mounted between said nose member and base plate, and being removable upon removing said nose member, a motor in said motor casing, means interconnecting said motor and roller for rotation, said means comprising an air rotor shaft supported on said pulley casing and cover, and disposed parallel to the axis of the motor, a pulley on the armature shaft of the motor, a pulley on said air rotor shaft, said pulleys being located within the pulley casing, an air rotor on said air rotor shaft, and disposed within said chamber, a worm on said air rotor shaft, a transverse shaft mounted for rotation within said chamber and disposed at right angles to the air rotor shaft, a worm wheel on said transverse shaft, meshing with said worm, a pinion on said transverse shaft, and a pinion on the roller meshing with the first pinion.

17. A device of the character described, comprising a motor casing open at its front end, a plate attached to the front end of the casing and extending below said casing, a pulley housing attached to said plate and extending below said plate, a base plate attached to the pulley housing and plate, the undersurface of the base plate being disposed below said motor casing, a cover member attached to the pulley housing and base plate, a transverse opening being formed between the base plate and the nose member at the underside of said device, a roller rotatably mounted between said nose member and base plate, and being removable upon removing said nose member, a motor in said motor casing, means interconnecting said motor and roller for rotation, said means comprising an air rotor shaft supported on said pulley casing and cover, and disposed parallel to the axis of the motor, a pulley on the armature shaft of the motor, a pulley on said air rotor shaft, said pulleys being located within the pulley casing, an air rotor on said air rotor shaft, and disposed within said chamber, a worm on said air rotor shaft, a transverse shaft mounted for rotation within said chamber and disposed at right angles to the air rotor shaft, a worm wheel on said transverse shaft, meshing with said worm, a pinion on said transverse shaft, a pinion on the roller meshing with the first pinion, the top of the motor casing extending above the top of the cover, and a strap handle interconnecting the motor casing with said cover.

18. A device of the character described, comprising a motor casing open at its front end, a plate attached to the front end of the casing and extending below said casing, a pulley housing attached to said plate and extending below said

plate, a base plate attached to the pulley housing and plate, the undersurface of the base plate being disposed below said motor casing, a cover member attached to the pulley housing and base plate, and forming a chamber therewith, a nose member attached to said cover member and base plate, a transverse opening being formed between the base plate and the nose member at the underside of said device, a roller rotatably mounted between said nose member and base plate, and being removable upon removing said nose member, a motor in said motor casing, means interconnecting said motor and roller for rotation, said means comprising an air rotor shaft supported on said pulley casing and cover, and disposed parallel to the axis of the motor, a pulley on the armature shaft of the motor, a pulley on said air rotor shaft, said pulleys being located within the pulley casing, an air rotor on said air rotor shaft, and disposed within said chamber, a worm on said air rotor shaft, a transverse shaft mounted for rotation within said chamber and disposed at right angles to the air rotor shaft, a worm wheel on said transverse shaft, meshing with said worm, a pinion on said transverse shaft, a pinion on the roller meshing with the first pinion, the top of the motor casing extending above the top of the cover, a strap handle interconnecting the motor casing with said cover, said handle comprising a pair of mutually contacting parts, and means for attaching said parts together.

19. A device of the character described, comprising a motor casing open at its front end, a plate attached to the front end of the casing and extending below said casing, a pulley housing attached to said plate and extending below said plate, a base plate attached to the pulley housing and plate, the undersurface of the base plate being disposed below said motor casing, a cover member attached to the pulley housing and base

40

plate, and forming a chamber therewith, a nose member attached to said cover member and base plate, a transverse opening being formed between the base plate and the nose member at the underside of said device, a roller rotatably mounted between said nose member and base plate, and being removable upon removing said nose member, a motor in said motor casing, means interconnecting said motor and roller for rotation, said means comprising an air rotor shaft supported on said pulley casing and cover, and disposed parallel to the axis of the motor, a pulley on the armature shaft of the motor, a pulley on said air rotor shaft, said pulleys being located within the pulley casing, an air rotor on said air rotor shaft, and disposed within said chamber, a worm on said air rotor shaft, a transverse shaft mounted for rotation within said chamber and disposed at right angles to the air rotor shaft, a worm wheel on said transverse shaft, meshing with said worm, a pinion on said transverse shaft, a pinion on the roller meshing with the first pinion, the top of the motor casing extending above the top of the cover, a strap handle interconnecting the motor casing with said cover, said handle comprising a pair of mutually contacting parts, means for attaching said parts together, said handle being formed with a through conduit, and said motor casing and cover being formed with openings registering with the ends of said conduit.
